REFRIGERATING APPARATUS

Robert R. Candor, Dayton, Ohio, assignor to General Motors Corporation, Dayton, Ohio, a corporation of Delaware

Application March 31, 1934, Serial No. 718,333
Renewed July 29, 1938

14 Claims. (Cl. 62—6)

This invention relates to refrigeration and more particularly to the conditioning of air for enclosures or vehicles.

An object of this invention is to provide an air conditioning system or method in which the normal refrigerating capacity of refrigerating system is utilized for conditioning the air directly or substantially at the same time that it is generated, and in which the excess refrigerating capacity to cool the holdover in an approved manner.

Further objects and advantages of the present invention will be apparent from the following description, reference being had to the accompanying drawings, wherein a preferred form of the present invention is clearly shown.

In the drawings:

Fig. 1 is a diagrammatic representation of an apparatus embodying features of my invention;

Fig. 2 is a diagrammatic representation of a slightly modified form of a portion of the apparatus shown in Fig. 1.

Fig. 3 is a vertical cross-sectional view of a modified form of holdover tank; and

Fig. 4 is a vertical cross-sectional view transverse to Fig. 3.

An air conditioning system embodying features of my invention includes, in general, a compartment or vehicle 10 the air for which is to be conditioned. A refrigerating system is associated with the compartment or vehicle 10 in such a manner that the system applies its refrigerating capacity to the air to be conditioned directly or at least substantially at the same time that refrigeration is produced so long as the system has sufficient capacity or excess capacity, and applies its excess refrigerating capacity for the cooling of the holdover which is thereafter utilized to condition the air when the refrigerating system lacks sufficient capacity to cool the air.

The refrigerating system includes a refrigerant liquefying unit 11, and a first evaporator 12 in refrigerant circulating relationship. It also includes a second evaporator 13 also in refrigerant circulating relationship with the refrigerant liquefying unit. The arrangement is such that evaporator 12 conditions air so long as the refrigerating capacity is equal to or in excess of the air conditioning requirements. The arrangement is such that the evaporator 13 cools a holdover 14 in an insulated sump 15 whenever the refrigerating capacity is in excess of the air conditioning requirements. Means are provided for conditioning the air by cooling it with the holdover 14 when the refrigerating system lacks sufficient

capacity either because it is operated at an insufficient speed or because its driving means are stopped altogether, as will be hereinafter more fully explained.

The refrigerant liquefying unit may include, in general, a compressor 16, condenser 17 and a liquid refrigerant receiver 18. The receiver 18 is connected with the evaporator 12 by means of a liquid refrigerant line 19 and the evaporated refrigerant returns to the compressor from the evaporator 12 through the evaporated refrigerant line 20. The evaporator 13 is connected with the receiver 18 through the liquid line 21, and the evaporated refrigerant for evaporator 13 returns to the compressor through the evaporator refrigerant line 22. An automatic expansion device is interposed between the receiver 18 and the evaporator 12. This may take the form of an automatic constant pressure valve 23 which feeds liquid refrigerant into the evaporator 12 whenever the pressure within the evaporator falls below a predetermined pressure. However, this valve is also provided with a thermostatic bulb 24 placed at the outlet of the evaporator 12 which automatically closes or throttles a valve 23 whenever liquid refrigerant in excess quantities reaches the zone where the bulb 24 is placed. This arrangement tends to maintain the evaporator 12 with sufficient liquid refrigerant to wet the internal surfaces from valve 23 to bulb 24. The evaporator 13 is also provided with an automatic expansion device in the form of a constant pressure valve 25 which tends to feed liquid refrigerant into the evaporator 13 whenever the pressure therein drops below a predetermined limit. The pressure at which the valve 25 feeds refrigerant is selected at a lower pressure than the setting for the valve 23. Thus the evaporator 12 receives liquid refrigerant in preference to the evaporator 13 so long as the refrigerating capacity of the unit 11 is only equal to or below the air conditioning requirements; but when unit 11 generates excess refrigerating capacity it tends to reduce the pressure in the suction line below the limit of the valve 23 which causes the valve 25 to supply liquid refrigerant to the evaporator 13 and to refrigerate holdover 14.

The refrigerant liquefying unit 11, when it is mounted on a vehicle, may be driven by any suitable means in functional relationship to the motion of the vehicle. Thus the compressor 16 may be directly driven from the axle 26 through the medium of a belt drive 27 or similar connection. The refrigerating capacity of unit 11 is therefore likely to change from time to time in response to

varying conditions of speed, temperatures, etc. At times, therefore, the unit 11 may have excess refrigerating capacity beyond the requirements of evaporator 12 and the other times it may have insufficient capacity and it is therefore desirable to prevent the unit 11 from reducing the temperature of the evaporator 12 below the desired temperature, which is generally slightly above 32° F. Also it is desirable to prevent the cooling of compartment 10 below a comfortable temperature. To this end, means are provided for throttling the flow of refrigerant from the evaporator 12 to the compressor 16. This may take the form of a valve 28 made responsive to air conditions through the medium of a thermostatic bulb 29 which throttles the suction line whenever the temperature of the air in compartment 10 reaches a predetermined low limit and opens the valve whenever the temperature rises above this limit or any higher limits selected. In addition, other throttling means are provided which prevent the compressor 16 from reducing the refrigerant temperature of evaporator 12 below 32° F., the freezing point of water. This may take the form of a constant pressure valve 30 which throttles the suction line 20 whenever the pressure in the evaporator 12 tends to fall below a predetermined limit, which limit is preferably selected to correspond to some temperature slightly above 32° F., but below the temperature desired for the air in compartment 10. It is to be understood that in the physical embodiment of the valves 28 and 30 their functions may be embodied in a single structure. The valve 28 may be of the type wherein an opening is gradually opened and closed by the bulb 29, or it may be of the type when the opening is suddenly opened and closed. In the latter case it may be convenient to provide a bleeding by pass, diagrammatically indicated at 28a, to permit a slight amount of refrigerant to pass at all times. In such a case, the valve 28 may be a solenoid valve energized and deenergized by thermostatic bulb 29. Bulb 29 may be made responsive to dry bulb or wet bulb temperatures or both, as desired. Means are provided for causing the evaporator 13 to cool the holdover 14 whenever the refrigerating capacity of unit 11 is in excess of the requirements of the evaporator 12. This may take the form of valved connections including a check valve 31 in the suction line 22 which permits evaporated refrigerant to flow to the compressor 16 whenever the compressor tends to lower the refrigerant pressure in its intake line 32 below the pressure maintained in the evaporator 12. Thus whenever any throttling action is imposed on the line 20 by either of the valves 28 or 30, the compressor 16 tends to evaporate refrigerant in the evaporator 13. If desired, a valve 33 is provided at the outlet of evaporator 13 which tends to throttle the line 22 wherever liquid refrigerant in sufficient quantities reaches thermal contact with the bulb 34 which tends to close the valve 33. This prevents the compressor 16 from drawing liquid refrigerant from the evaporator 13 and prevents waste of refrigeration by evaporation in the suction line 22.

Preferably the holdover sump or storage zone 15 is placed underneath the floor of the car 10 and therefore it is convenient to provide means for circulating the holdover from the sump 15 to an air condition zone, which may be conveniently adjacent to air conditioning zone occupied by the evaporator 12. Thus a pump 40 is provided with a suction line 41 in the sump 15, which pumps holdover through the line 42 to the air condition-

ing zone in coil 43 in the path of air blown by the electrically driven blower or fan 44. The holdover returns through the line 45 to the sump 15. In the physical embodiment, the pump 40 is placed sufficiently low to be self priming at all times. Means are provided for operating the pump 40 whenever the refrigerating capacity of unit 11 falls below a predetermined limit. This may be accomplished by drivingly connecting the pump 40 with an electric motor 46 which is automatically energized whenever the speed of the car falls below a predetermined limit and preferably also only when the temperature of the compartment 10 rises above a predetermined comfort limit. Thus an electric energizing circuit is provided for the motor 46 which includes a battery 47, a centrifugal switch 48 drivingly connected with the wheel 49 and responsive to car speed, and a thermostat 50 which is responsive to temperatures of air in compartment 10. The calibrations are such that the centrifugal switch 48 closes whenever the speed of the car falls below a predetermined limit and the thermostatic switch 50 closes whenever the temperature of the car rises above a predetermined comfort limit. The battery 47 may conveniently be a storage battery which is charged by the generator 51, having a suitable centrifugal cut out which is drivingly connected with the wheel 49. The motor driven fan 44 may also be driven by electrical energy derived from the battery 47 and which may be controlled by a switch 52 which may be either manually controlled or thermostatically controlled in response to temperatures in compartment 10.

The holdover may be of any type desired. Preferably it is a liquid adapted to be frozen by the evaporator 13. Thus water may be used, and the evaporator 13 is spaced a sufficient distance from the suction pipe 41 to prevent the formation of ice around it. After a cake of ice of a certain thickness is formed on the evaporator 13, the heat infiltration into the sump 15 is equal to the heat transfer to the evaporator 13 through the cake of ice. When these conditions are reached, no further ice is formed. The pipe 41 is placed beyond this limit, and hence the pump intake is always free. The liquid returning to the sump 15 through the pipe 45 is distributed over and flows around the ice and is properly cooled before being repumped through the cooling pipe 43.

Means are provided for preventing overloading of the refrigerating system when condenser pressures rise above a safe limit. Thus a valve 53 is provided in the suction line 32 which throttles the compressor intake whenever condenser pressures rise above safe limits. The valve 53 may have its actuating bellows connected by the pipe 54 with the discharge 55 of the compressor and may be calibrated to throttle or close the suction line 32 at any predetermined discharge pressure limit desired.

In the modification shown in Fig. 2, the compressor 16a is driven from the wheel 61 of the car by an automatic ratio changing transmission 62, which is interposed between the compressor and the wheel. The automatic transmission 62 may include an automatic governor which automatically changes the drive ratio between the wheel and the compressor as the speed of the car varies. The speed of the compressor 16a need not be maintained absolutely constant, although if desired the transmission may be selected to do so. Preferably, however, the transmission 62 includes a centrifugal governor which

automatically declutches the drive and changes gear ratio under varying compressor speeds in a manner similar to transmissions, now interposed between the internal combustion engine and the wheel of automobiles. Numerous transmissions of this type are well known and their specific description is deemed unnecessary. The remainder of the system may be as shown in Fig. 1.

If desired means may be provided for stopping the operation of the compressor after the compartment 10 has been properly cooled and after the proper amount of ice has been formed in the holdover sump. Thus a thermostatic bulb 63 may be placed in sump 15a (which corresponds to sump 15 in Fig. 1) which closes switch 65 and energizes a solenoid 66. Thus solenoid 66 declutches the clutch in transmission 62 or a supplementary clutch, if desired, and stops the compressor. Thereafter the compressor is not actuated until ice has melted away from bulb 63 in sump 15a either because of heat infiltration into the sump or because of circulation of water to the air conditioning zone in response to air conditioning demands through control of a thermostat 50.

In certain embodiments, it is desirable to provide means permitting the use of auxiliary refrigeration where the car stands idle after the holdover refrigerating power has been consumed. This may be accomplished by the use of a modified form of sump in the system shown in Fig. 1. The sump 15 of Fig. 1, under such circumstances may take the form shown in Figs. 3 and 4. The sump may be suspended under the car with the side 100 adjacent the side of the car. The sump is provided with a water, or other holdover, section 101, and with an auxiliary ice section 102. The section 101 is provided with an evaporator 103 corresponding to evaporator 13 of Fig. 1. A pipe 104 leads to a pump similar to 40 and the holdover returns to the sump through pipe 105 from an air cooling section similar to 43 of Fig. 1. The pipe 105 is provided with a plurality of spray heads 106. The auxiliary ice section 102 is provided with ice supporting racks 107 and vertical baffles 108. One or more cakes of ice 109 or other refrigerating means, are inserted through a door 110, which swings about hinges 111 and is fastened at 112. An overflow pipe 113 is provided with a hand or automatic valve 114 to drain excess water accumulating in the system from the melting ice.

When the train is to stand for an abnormally long period of time, or when it is desired to pre-cool the train before it starts at the terminal, cakes of ice 109 are transferred from a station truck, not shown, into the section 102 of each car to be refrigerated. The pump corresponding to 40 operates under control of thermostat 50 and pumps water from pipe 104 to an air cooling section corresponding to 43. The water, with heat from the air, returns through pipe 105 and is sprayed over the cakes of ice 109 where it is cooled and drains into section 101. The cycle is repeated as long as ice remains in the sump. Thus the car is maintained at a comfortable temperature until it starts and is refrigerated by the system as described with respect to Fig. 1.

While the form of embodiment of the present invention as herein disclosed, constitutes a preferred form, other forms might be adopted, all coming within the scope of the claims which follow.

What is claimed is as follows:

1. An air conditioning system for a vehicle comprising a compressor, condenser and evaporator in refrigerant circulating relationship and associated with said vehicle, said evaporator being in heat exchange with air to be conditioned for said vehicle, means for driving said compressor in functional relationship to the motion of the vehicle, a refrigerant expansion means between said condenser and evaporator, and refrigerant throttling means between said evaporator and compressor responsive to condenser conditions. 5

2. An air conditioning system for a vehicle comprising a compressor, condenser and evaporator in refrigerant circulating relationship and associated with said vehicle, said evaporator being in heat exchange with air to be conditioned for said vehicle, means for driving said compressor in functional relationship to the motion of the vehicle, means for throttling the flow of the evaporated refrigerant from said evaporator to said compressor when said compressor attains excess refrigerating capacity in relation to the refrigerating demands upon said evaporator, a second evaporator connected to said compressor, and means for cooling a holdover with said second evaporator when said compressor attains excess refrigerating capacity. 10 15 20 25

3. An air conditioning system for a vehicle comprising a compressor, condenser and evaporator in refrigerant circulating relationship and associated with said vehicle, said evaporator being in heat exchange with air to be conditioned for said vehicle, means for driving said compressor in functional relationship to the motion of the vehicle, means for throttling the flow of evaporated refrigerant from said evaporator to said compressor when said compressor attains excess refrigerating capacity in relation to the refrigerating demands upon said evaporator, a second evaporator connected to said compressor to operate at a lower temperature than said first evaporator, a sump containing liquid holdover, means for exchanging heat between holdover and air to be conditioned, a pump for circulating holdover from said sump to said last named means, said second evaporator being in thermal exchange relationship with the holdover in said sump. 30 35 40 45 50

4. An air conditioning system for a vehicle comprising a compressor, condenser and evaporator in refrigerant circulating relationship and associated with said vehicle, said evaporator being in heat exchange with air to be conditioned for said vehicle, means for driving said compressor in functional relationship to the motion of the vehicle, means for throttling the flow of evaporated refrigerant from said evaporator to said compressor when said compressor attains excess refrigerating capacity in relation to the refrigerating demands upon said evaporator, a second evaporator connected to said compressor to operate at a lower temperature than said first evaporator, a sump containing liquid holdover, means for exchanging heat between holdover and air to be conditioned, a pump for circulating holdover from said sump to said last named means, said second evaporator being in thermal exchange relationship with the holdover in said sump and means for automatically starting said pump when the speed of the car falls below a predetermined limit. 55 60 65 70

5. An air conditioning system for a vehicle comprising a compressor, condenser, and evap- 75

- orator in refrigerant circulating relationship and associated with said vehicle, said evaporator being in heat exchange with air to be conditioned for said vehicle, means for driving said compressor in functional relationship to the motion of the vehicle, means for throttling the flow of evaporated refrigerant from said evaporator to said compressor when said compressor attains excess refrigerating capacity in relation to the refrigerating demands upon said evaporator, a second evaporator connected to said compressor to operate at a lower temperature than said first evaporator, a sump containing liquid holdover, means for exchanging heat between holdover and air to be conditioned, a pump for circulating holdover from said sump to said last named means, said second evaporator being in thermal exchange relationship with the holdover in said sump and means for controlling the operation of said pump in accordance with air conditions.
6. An air conditioning system for a vehicle comprising a compressor, condenser and evaporator in refrigerant circulating relationship and associated with said vehicle, said evaporator being in heat exchange with air to be conditioned for said vehicle, means for driving said compressor in functional relationship to the motion of the vehicle, means for throttling the flow of evaporated refrigerant from said evaporator to said compressor when said compressor attains excess refrigerating capacity in relation to the refrigerating demands upon said evaporator, a second evaporator connected to said compressor to operate at a lower temperature than said first evaporator, a sump containing liquid holdover, means for exchanging heat between holdover and air to be conditioned, a pump for circulating holdover from said sump to said last named means, said second evaporator being in thermal exchange relationship with the holdover in said sump and means for starting said pump when the refrigerating capacity of said compressor falls below a predetermined limit.
7. Refrigerating apparatus comprising a compressor, condenser and refrigerant evaporating means, an evaporated refrigerant line connecting said evaporating means and the intake of said compressor, a liquid refrigerant line connecting said condenser and said evaporating means, throttling means in said evaporated refrigerant line effective to throttle the flow of refrigerant into said compressor when the refrigerant pressure in said evaporated refrigerant line falls below a predetermined limit and when the refrigerant pressure in said condenser rises above a predetermined limit.
8. An air conditioning system for a vehicle comprising a compressor, condenser and evaporator in refrigerant circulating relationship and associated with said vehicle, said evaporator being in heat exchange relation with air to be conditioned for said vehicle and subjected to variable refrigeration loads in response to extraneous conditions, means for driving said compressor in functional relationship to the varying speeds of the vehicle thereby imposing a variable capacity on said compressor, a refrigerant expansion means between said condenser and evaporator, and refrigerant throttling means between said evaporator and compressor to balance said variable refrigeration load and said variable compressor capacity.
9. An air conditioning system for a vehicle comprising a compressor, condenser and evaporator in refrigerant circulating relationship and associated with said vehicle, said evaporator being in heat exchange relation with air to be conditioned for said vehicle and subjected to variable refrigeration loads in response to extraneous conditions, means for driving said compressor in functional relationship to the varying speeds of the vehicle thereby imposing a variable capacity on said compressor, a refrigerant expansion means between said condenser and evaporator, and refrigerant throttling means between said evaporator and compressor, responsive to air conditions, to balance said variable refrigeration load and said variable compressor capacity.
10. An air conditioning system for a vehicle comprising a compressor, condenser and evaporator in refrigerant circulating relationship and associated with said vehicle, said evaporator being in heat exchange relation with air to be conditioned for said vehicle and subjected to variable refrigeration loads in response to extraneous conditions, means for driving said compressor in functional relationship to the varying speeds of the vehicle thereby imposing a variable capacity on said compressor, a refrigerant expansion means between said condenser and evaporator, and refrigerant throttling means between said evaporator and compressor, responsive to air conditions, to balance said variable refrigeration load and said variable compressor capacity.
11. An air conditioning system for a vehicle comprising a compressor, condenser and evaporator in refrigerant circulating relationship and associated with said vehicle, said evaporator being in heat exchange relation with air to be conditioned for said vehicle and subjected to variable refrigeration loads in response to extraneous conditions, means for driving said compressor in functional relationship to the varying speeds of the vehicle thereby imposing a variable capacity on said compressor, a refrigerant expansion means between said condenser and evaporator, and refrigerant throttling means between said evaporator and compressor limiting the fall in pressure in said evaporator below a predetermined limit to balance said variable refrigeration loads and said variable compressor capacity to maintain the refrigerant pressure in said evaporator sufficiently high to prevent formation of ice on said evaporator.
12. An air conditioning system for a vehicle comprising a mechanical refrigerating system operated by power derived from a live axle, means for thermally contacting air for a compartment of said car and for thermally contacting a holdover with the cooling portion of said mechanical refrigerating system, an ice bunker on said vehicle, and means for cooling said holdover and for cooling air for said compartment by ice in said bunker to augment the refrigeration produced by said mechanical refrigerating system.
13. In combination with a vehicle having a live axle, an air conditioning system for a passenger compartment of said vehicle comprising a mechanical refrigerating system producing refrigeration derived from power from said axle, holdover cooling means cooperating with said mechanical refrigerating system and refrigerated

by said mechanical refrigerating system when said mechanical refrigerating system has excess capacity, and means for providing stand-by refrigeration supplemental of the refrigeration produced by said axle for cooling air for said compartment and for cooling said holdover when said vehicle is standing and when said holdover lacks sufficient capacity to cool the air.

14. In combination with a vehicle having a live axle, means for conditioning the air for a passenger compartment of said vehicle comprising a mechanical refrigerating system for pro-

ducing refrigeration derived from power supplied by said axle, holdover cooling means cooperating with said mechanical refrigerating system and refrigerated by said mechanical refrigerating system when said mechanical refrigerating system has excess capacity, and means for providing stand-by refrigeration supplemental to the refrigeration produced by the axle for cooling air for said compartment, said last named means serving to cool said holdover so as to increase the holdover capacity thereof.

ROBERT R. CANDOR.
